UNITED STATES PATENT OFFICE.

PAUL M. HOTCHKIN, OF CHICAGO, ILLINOIS, ASSIGNOR TO THE NATIONAL X-RAY REFLECTOR COMPANY, OF CHICAGO, ILLINOIS, A CORPORATION OF ILLINOIS.

COLOR LIGHTING ATTACHMENT FOR REFLECTORS.

Application filed February 24, 1920. Serial No. 360,822.

To all whom it may concern:

Be it known that I, PAUL M. HOTCHKIN, a citizen of the United States, residing at Chicago, in the county of Cook and State of Illinois, have invented certain new and useful Improvements in Color Lighting Attachments for Reflectors, of which the following is a specification.

The present invention relates to the art 10 of display lighting and is more particularly concerned with instrumentalities for the production of colored effects in connection with such lighting.

The primary object of the invention is to 15 provide a novel form of attachment for the reflectors usually employed in display lighting, whereby to color the light rays emanating from the reflectors, and thereby to obtain colored effects on the objects to which 20 the light is directed.

A further object of the invention is to 25 embody such an attachment in the form of an adapter that may be manufactured in standard form so as to fit standard reflectors, the construction being such as to 30 enable its ready application to and removal from the reflectors, and which, when so applied, will permit access freely to be had to the interior of the reflectors for cleaning the same or replacing the lamps used therewith.

Furthermore, the invention seeks to 35 provide an attachment of the class referred to wherein the coloring media may be expeditiously changed when such is desired in order to modify the color scheme to meet varying requirements, and to so construct the attachment that it shall possess marked 40 advantages in point of first cost, maintenance, appearance and ease with which it may be procured.

Other objects and advantages will appear 45 as the nature of the invention is better understood, the latter consisting substantially in the novel construction, combination and arrangement of parts hereinafter fully described, illustrated in the accompanying drawings, and finally pointed out in the appended claims.

50 A practical embodiment of the invention is herein presented to disclose the adaptability of the same to the purposes for which it is intended, but this disclosure

is to be considered only in an illustrative sense and is not to be taken as imposing 55 limitations on the invention.

In the drawings—

Fig. 1 is a top plan view of a reflector for lighting fixtures equipped with a color attachment constructed in accordance with 60 the present invention.

Fig. 2 is a longitudinal sectional view thereof, as on the line 2—2, Fig. 1.

Fig. 3 is a transverse sectional view, parts being broken away as on the line 3—3, 65 Fig. 1.

Referring in detail to the accompanying drawings, the numeral 10 designates a reflector of standard form commonly employed in display lighting, the same being 70 of the parabolic type frequently used in the illumination of the display windows of stores and in the like localities. This reflector has the usual contracted neck 11 at its upper portion for encircling an electric 75 light bulb and is, of course, open at its lower end for ready passage of the light rays reflected thereby.

As indicated, the present invention is an attachment for coloring the light rays 80 emanating from the reflector 10. It contemplates the employment of an adapter generally in the form of a rectangular frame 12 the top of which is provided with an enlarged opening 13 the dimensions of 85 which are substantially the same as the dimensions of the open end of the reflector 10. Surrounding the opening 13 is an upstanding flange 14 which is designed to fit the inner walls of the reflector 10 at its 90 mouth and thereby to enable the adapter to be fitted to the reflector. The flange 14, when the frame 12 has been fitted to the reflector, also prevents relative crosswise movement of the adapter and the reflector, 95 thus maintaining the color screen in proper position over the reflector to receive the light rays therefrom.

The adapter 12 is provided with side flanges 15, a rear flange 16 which extends 100 between the rear ends of the side flanges 15, and a front flange 17. The front flange 17 is of less width than the side and rear flanges 15 and 16, respectively, and this provides a mouth at the forward end of the 105 adapter 12 for permitting introduction and

removal of the color screen to and from the adapter. This is designated by the numeral 18, and it may be made of glass, gelatin or other material suitable for the 5 purpose and of the required color. For protecting the screen 18 against breakage it may be provided at its opposite sides with wire mesh fabric 19. This is especially desirable if the screens be made of gelatin or 10 such material as is easily fractured.

The screen 18 is supported by horizontal inwardly extending guide flanges 20 formed at the lower edges of the side walls 15 and spaced a suitable distance below the top of 15 the adapter 12 for facilitating free movement of the screen into and from the adapter. When inserted within the adapter the rear end of the screen will abut against the rear wall 16 and thereby be prevented 20 becoming displaced at the rear end of the adapter.

To sustain the adapter 12 in assembled relation with respect to the reflector 10 a supporting loop 21 is employed. This loop may 25 be of any desired flexible material and is adapted to embrace the neck 11 of the reflector 10 as clearly illustrated in Fig. 1, and to fit over the upper portion of said reflector. One end of the loop 21 has an attaching strap 22 which is suitably connected to the rear end of the adapter 12, a flexible coupling 23, preferably in the form of a coil spring, being connected to the other end of the supporting loop 21 and provided with a 30 hook 24 adapted to engage an opening formed in the flange 17 at the front of the adapter. It will thus be seen that the adapter is yieldingly connected to and supported by the reflector 10, and by simply disengaging the hook 24 from the flange 17 the supporting loop 21 may be readily removed 35 from about the neck of the reflector to permit detachment of the adapter from the reflector.

40 In the use of the herein-described invention screens of the desired color are inserted in the adapter and thereby intercept the light rays emanating from the reflector 10. Differently colored screens may be substituted 45 from time to time in order to change the colored effects produced by the screens, and this may be accomplished by simply sliding the screen outwardly from the adapter, and thereby overcoming necessity 50 of removing the adapter from the reflector for effecting such change. Access also may be readily had to the interior of the reflector by the removal of the color screen 18, either for cleaning the interior of the 55 reflector or relamping the same.

For ventilating the attachment the top 60 thereof is provided at its corners, and at points therein which lie at the exterior of the reflector when the attachment is assembled thereon, with a plurality of open-

ings 25. These openings are in direct communication with the space above the screen 18.

I claim:

1. An attachment of the class described, 70 comprising a supporting frame having an opening therein for passage of light rays, oppositely-disposed guide flanges arranged at the sides of said frame, a displaceable color screen supported by said guide flanges 75 to intercept the light rays passing through said opening, said guide flanges providing an opening for the insertion of said screen accessible when the frame is in position on a reflector, and means for attaching said frame to a light reflector.

2. An attachment of the class described, 80 comprising a supporting frame having an opening therein for passage of light rays, an upstanding flange surrounding said opening to adapt said frame to the reflector with which the same is associated, a color screen supported by said frame to intercept the light rays passing through said opening, and 85 means for attaching said frame to said light reflector.

3. An attachment of the class described, 90 comprising a supporting frame having an opening therein for passage of light rays, a pair of guide flanges arranged at opposite 95 sides of said frame, a color screen slidably mounted on said guide flanges and adapted to intercept the light rays passing through said opening, said guide flanges providing an opening for the insertion of said screen 100 accessible when the frame is in position on a reflector, means at one end of said guide flange for limiting movement of said color screen over said flanges, and means for attaching said frame to a light reflector. 105

4. An attachment of the class described, 110 comprising a box-like supporting frame having an opening at one side for passage of light rays and provided at said opening with means for adapting the frame to the 115 configuration of a light reflector, said frame also having oppositely disposed flanges and an opening affording access to said flanges, a color screen displaceably mounted on said flanges to intercept the light rays passing through said frame and movable into and from the latter through said opening affording access to said flanges, the last-mentioned opening being accessible for insertion of the 120 screen when the frame is in position on a reflector, and means for attaching said frame to a light reflector.

5. An attachment of the class described, 125 comprising a box-like supporting frame having an opening at one side for passage of light rays and provided with an upstanding flange surrounding said opening for fitting the configuration of a light reflector to adapt the supporting frame to the light reflector, said frame also having oppositely 130

disposed flanges and an opening affording access to said flanges, a color screen displaceably mounted on said flanges to intercept the light rays passing through said frame and movable into and from the latter through said opening affording access to said flanges, the last-mentioned opening being accessible for insertion of the screen when the frame is in position on a reflector, and means for attaching said frame to a light reflector.

6. In a lighting fixture, the combination with a light reflector, of a color adapter therefor including a frame detachably associated with the reflector and open to passage

of light rays emanating from said reflector, said adapter having means conforming to the configuration of the reflector to fit the adapter thereto, a color screen displaceably mounted in said adapter to intercept the light rays passing therethrough, and means for detachably connecting the adapter to the light reflector.

In testimony whereof I have hereunto subscribed my name in the presence of two subscribing witnesses.

PAUL M. HOTCHKIN.
